UNITED STATES PATENT OFFICE.

ANNA L. PINKERTON-GARDINER, OF LOS ANGELES, CALIFORNIA.

DESIGN FOR AN INCUBATOR.

No. 39,212.

Specification for Design.

Patented March 17, 1908.

Application filed December 7, 1907. Serial No. 405,620. Term of patent 14 years.

To all whom it may concern:

Be it known that I, ANNA L. PINKERTON-GARDINER, a citizen of the United States, residing at Los Angeles, county of Los Angeles, and State of California, have invented a new, original, and ornamental Design for Incubators, of which the following is a specification, reference being had to the accompanying drawing, forming a part thereof.

The figure is a perspective view of an incubator showing my original design.

I claim:

The ornamental design for an incubator as shown.

ANNA L. PINKERTON-GARDINER.
